UNITED STATES PATENT OFFICE.

EDWIN BENNETT, OF BALTIMORE, MARYLAND.

ROOFING-TILE.

SPECIFICATION forming part of Letters Patent No. 351,956, dated November 2, 1886.

Application filed December 10, 1885. Serial No. 185,226. (No model.)

To all whom it may concern:

Be it known that I, EDWIN BENNETT, a citizen of the United States, residing at Baltimore, in the State of Maryland, have invented 5 certain new and useful Improvements in Roofing-Tiles, of which the following is a specification.

My invention relates to a roofing-tile. It consists of a tile of peculiar shape, and having 10 certain features of construction whereby the lap or joint formed in laying them on a roof is made to effectually exclude rain and snow.

In the accompanying drawings, which illustrate 15 this invention, Figure 1 is a top view of several of this tiles as they appear when assembled on a roof. Fig. 2 is a longitudinal section on the line *x* of Fig. 1. Fig. 3 is a side view of one tile and a longitudinal section of 20 two others, showing the relative position, when on the roof, of certain parts of the tiles. Fig. 4 is a cross-section on the line *y* of Fig. 1, showing the lap of the tiles. Fig. 5 is a view of the lower end of a tile. Fig. 6 is a bottom 25 view of one tile. Fig. 7 is a top view of one tile. Fig. 8 is an end view of a tile, showing a modification in the shape of the drain- surface.

The tile may be made of any suitable material, such as metal, glass, or clay.

Each tile has a flat upper surface, *A*, at one side of which is an upright longitudinal flange, *B*, which has on its inner side a shoulder, *c*, near the upper end, to act as a stop or seat for 35 the lower end, *d*, of the flange on the next upper overlapping tile, and an offset, *e*, near the lower end, to take position above the upper end, *f*, of the next side overlapping tile. At the other side of the flat upper surface, *A*, is 40 a convex-curved part, *G*, which, commencing at the flat surface, curves upward and then down, terminating with a downward-pointing longitudinal edge, *h*, which laps over part of the upright flange *B*, on each of the two side 45 adjoining tiles. This upward-curved part *G* is largest at the lower end, *i*, and tapers toward the upper end, *f*. By this construction the outer dimension across this convex-curved part at the upper end, *f*, may correspond to

the inner dimension across the lower end, *i*. 50 Thereby the lower end of said convex-curved part of one tile may lap over the upper end of the same part of another tile, as shown in Fig. 1. The downward-pointing edge *h* is cut away at the upper end, as at *k*, (see Fig. 3,) so that 55 said cut-away part may be seated on the lower portion of the flat surface *A* of one tile, while the remainder of said edge *h* may be seated on the whole of the exposed portion of the flat surface of the next lower tile. 60

The flat lower surface, *L*, of the tile has a gain or cut-away, *n*, at that portion, which, on the roof, will overlap the upper end of the tile next below. This gain or cut-away is to reduce the thickness of the tile at that part, and 65 thereby secure a closer fit or "set-down" on the tile next below.

The extent to which an upper tile will overlap another below is determined by the shoulder *c* on the upright flange *B*. As the upper 70 end, *f*, of the downward-pointing edge *h* is guarded by the offset *e* on the tile next above, rain-water running down the flat surface *A* will not enter the joint. Each tile has nail-holes *p* through the upper flat surface, by which 75 it is secured to the wood-work of a roof. A tile thus shaped and constructed will make a tight roof.

The drain-surface *A* has been described as being flat; but it is obvious it may be somewhat curved, as shown in Fig. 8. For roofs of certain shape this curved surface *A* would be necessary. Therefore where the words "flat surface" are herein used I design them to include a slightly-curved surface. 85

Having described my invention, I claim and desire to secure by Letters Patent of the United States—

1. A roofing-tile comprising a flat surface, *A*, having at one side an upright longitudinal flange, *B*, provided on its inner side, and near its lower end, with an offset, *e*, and at the other a convex-curved part, *G*, which terminates in a downward-pointing longitudinal edge, *h*, as set forth. 90

2. A roofing-tile comprising a flat surface, *A*, having at one side an upright longitudinal flange, *B*, provided on its inner side with a

shoulder, *c*, to stop the next upper overlapping tile, and at the other a part which terminates in a downward-projecting longitudinal edge, *h*, as set forth.

5 3. A roofing-tile comprising a flat lower surface, *L*, having a gain or cut-away, *n*, at that part which will overlap a tile next below it, and a flat upper surface, *A*, having at one side an upright longitudinal flange, *B*, and at the

other a part which terminates in a downward-projecting longitudinal edge, *h*, as set forth. 10

In testimony whereof I affix my signature in presence of two witnesses.

EDWIN BENNETT.
